ALONZO C. BLACK AND JOSEPH D. CLARK, OF DES MOINES, IOWA.

LOCKING-VALVE FOR FUEL-TANKS.

1,377,389.

Specification of Letters Patent. Patented May 10, 1921.

Application filed May 26, 1919. Serial No. 299,734.

To all whom it may concern:

Be it known that we, ALONZO C. BLACK and JOSEPH D. CLARK, citizens of the United States of America, and residents of Des Moines, Polk county, Iowa, have invented a new and useful Locking-Valve for Fuel-Tanks, of which the following is a specification.

The object of this invention is to provide an improved locking valve for fuel supply tanks.

A further object of this invention is to provide improved means for preventing unauthorized use of a motor vehicle by cutting off and locking the outlet to the fuel tank thereof.

A further object of this invention is to provide an improved rotary valve device for cutting off the outlet to a fuel tank, said valve being operable by a removable key of a locking mechanism.

A further object of this invention is to provide improved means for mounting a locking valve in a fuel tank.

A further object of this invention is to provide an improved construction whereby a lock of a common type is adapted for use with a rotary valve, for a particular purpose.

Our invention consists in the construction, arrangement and combination of elements hereinafter set forth, pointed out in our claims and illustrated by the accompanying drawing, in which—

Figure 1 is a cross-section through a fuel tank, illustrating our improved locking valve in open position. Fig. 2 is a section at right angles to Fig. 1.

In the construction of the device as shown the numeral 10 designates a tank adapted to contain gasoline or other liquid fuel, which tank is formed with an outlet 11 in its bottom from which the liquid fuel may be led by a suitable pipe (not shown) to a carburetor or other place of use. A small hole 12 is formed in the top of the tank 10 directly over the outlet 11, and a lock 13, of any suitable variety, such as the pin-tumbler type, is mounted with its escutcheon 14 against the inner face of the tank wall so that its key slot registers with the hole 12. Screws 15 are mounted through the tank wall adjacent the hole 12 and are seated in the lock body 13 and serve to hold the lock, and other members connected therewith, firmly in

place relative to the tank. The screws 15 may be sealed in place by soldering over their heads, to prevent tampering with the locking mechanism. The lock 13 has the usual rotary plug or barrel 16, operable by a removable key 17, and adapted to be immovably connected by the locking mechanism to the lock body when said key is withdrawn.

A tubular valve casing 18 is secured in upright position within the tank 10 and in a position surrounding the outlet 11, said valve casing being formed with a lateral inlet opening 19 near the bottom of the tank. A socket member 20 is mounted on the outside of the tank 10 in a position surrounding the outlet 11, and said socket member and the valve casing 18 are suitably secured to the tank wall to make a rigid and liquid-tight joint. The socket member 20 is adapted to receive a connection of the fuel line pipe. A rotary valve member 21 is mounted in and projects at its upper end from the casing 18, and said valve is formed with an L-shaped port 22 communicating at its outer end with the outlet 11 and adapted to communicate at times at its inner end with the inlet opening 19 of the casing. A semi-circumferential slot 23 is formed in the valve casing 18 and a pin 24 is mounted radially in the valve member 21 and projects at one end through said slot. It is the function of the pin 24 to limit rotation of the valve 21 relative to the casing, by engaging one end of the slot 23 when the inner end of the port 22 is in register with the inlet opening 19, when the valve is in open position, and by engaging the other end of the slot when said valve has been turned substantially a half turn, or 180 degrees, from such open position.

Any suitable means may be provided for connecting the rotary valve member 21 to the rotating member 16 of the lock, either directly or through intermediate members. Inasmuch as the common types of locks such as here shown ordinarily require a complete revolution of the locking member, such as 16, and consequently of the key 17, to turn from unlocked to locked position and permit withdrawal of the key, we have provided a slip connection between said locking member and the rotary valve in order that such complete revolution of the locking member and key will result in but a half

revolution of the valve. A sleeve 25 is rotatably mounted on the projecting upper end portion of the valve member 21 and projects above the top of said valve member. 5 A flat link 26 enters the upper end of the sleeve 25 and is connected thereto by a pin 27, so that rotation of said link results in rotation of said sleeve. The link 26 may be connected directly to the rotating member 10 16 of the lock if desired. We have deemed it best to provide an adjustable connection, so that the device may be adapted to use in tanks of different sizes, where the distance from the lock to the outlet varies. 15 Therefore a separate link member 28 is rigidly secured to the rotating lock member 16 and projects downwardly within the tank, and said link member is connected to the link member 26 by a telescoping member 29, here shown as embracing and frictionally engaging said members, and adapted to permit greater or lesser separation thereof and at the same time provide a connection whereby rotary movement of the 25 lock member 16 is transmitted to the sleeve 25.

A pin 30 is mounted radially in the upper portion of the rotary valve member 21 and projects at one end through a semi-circumferential slot 31 in the sleeve 25. This is the only connection between the sleeve and valve. The pin 30 projects in the opposite direction from the pin 24, and in turning the key 17 from locked to open position 35 the sleeve 25 first turns freely on the valve 21 for a half revolution, after which a connection is formed by engagement of the projecting end of the pin 30 with one end of the slot 31, and further turning of the 40 key results in a turning of the valve 21, for a half revolution, until stopped in open position by the pin 24. A similar action takes place in turning the key from the open to closed or locking position.

45 It is to be understood that the slip connection above described between the lock and valve may be dispensed with where a special or other lock is employed which requires but a half revolution of the key 50 from locked to unlocked position, and vice-versa.

This invention provides a simple, convenient and effective means for preventing unauthorized use of a motor vehicle, by cutting 55 off the fuel supply and locking it in such position by simply removing the key when the driver leaves the vehicle.

The members of the valve and locking mechanism may be inserted in the tank by 60 removal of an end wall thereof, or in the construction of the tank before such end wall is secured in place.

It is to be understood that modifications may be employed, within the scope of the

appended claims, without departing from 65 the spirit of our invention.

We claim as our invention—

1. The combination with a tank having an outlet, of a valve casing inclosing said outlet and having a lateral inlet opening, a 70 rotary valve mounted in said casing and having a port adapted to form communication at times between said inlet opening and the outlet, a key-controlled lock secured to said tank and having a rotary 75 member connected with said valve, said casing being formed with a semi-circumferential slot, and a pin in said valve extending through said slot and adapted to provide a stop means to limit rotary move- 80 ment of said valve.

2. The combination with a tank having an outlet, of a tubular valve casing mounted in said tank and inclosing said outlet, said casing being formed with a lateral inlet, a 85 rotary valve mounted in said casing and projecting at one end therefrom, said valve being formed with a port adapted to provide communication at times between said inlet opening and the outlet, a key-con- 90 trolled lock secured to said tank and having a rotary member, a sleeve rotatably mounted on the projecting end of said valve, said sleeve being formed with a semi-circumferential slot, a pin in said valve extending 95 through said slot and adapted to form a slip connection between the sleeve and valve, and connections between the lock rotary member and said sleeve for rotating the latter. 100

3. The combination with a tank having an outlet, of a tubular valve casing mounted in said tank and inclosing said outlet, said casing being formed with a lateral inlet opening, a rotary valve mounted in and projecting at one end from said casing and formed with a port adapted to provide communication between said inlet opening and the outlet, said casing being formed with a semicircumferential slot, a pin in said valve projecting through said slot, a key-controlled lock mounted in said tank having a rotary member, a sleeve rotatably mounted on the projecting portion of said valve, connections between the lock rotary member and said sleeve for producing rotary movement of the latter, said sleeve being formed with a semicircumferential slot, and a pin in said valve projecting through the latter slot, the last-named pin projecting 110 from said valve in a direction diametrically opposite to the first-mentioned pin. 115

Signed at Des Moines, in the county of Polk and State of Iowa, this 11th day of April, 1919.
